FIG. 8.

FIG. 9.

UNITED STATES PATENT OFFICE.

KATSUJIRO SANWO, OF FRESNO, CALIFORNIA.

TRAY-TURNING MACHINE.

1,323,552.

Specification of Letters Patent.

Patented Dec. 2, 1919.

Application filed May 22, 1919. Serial No. 299,063.

To all whom it may concern:

Be it known that I, KATSUJIRO SANWO, a subject of the Emperor of Japan, residing at Fresno, in the county of Fresno and State 5 of California, have invented new Tray-Turning Machines, of which the following is a specification.

This invention relates to a new and useful machine particularly adapted for turning 10 trays, and for discharging the contents of one tray into another.

The present method of handling grapes, consists in gathering the grapes on trays which are placed in a row, and left to dry 15 in the sun. When the grapes are dried upon the upper or exposed side, two operators pass along the row of trays and place an empty tray with bottom uppermost, on the consecutive trays, and turn the trays to reverse 20 position so that the grapes will fall into the empty tray to dry in the sun on the opposite side. The empty tray is then placed on the next successive full tray and the operation is repeated until all the grapes 25 have been turned within the trays.

The object of the present invention is to provide a machine which may pass along the 30 row of trays and perform the operation of gathering each tray from the ground, placing an empty tray thereon, reversing the position of the trays, depositing the tray containing the turned grapes upon the ground, and placing the empty tray upon the next successive tray containing grapes. The 35 machine is designed to perform all these functions while passing along the row.

With these ends in view the invention consists in the improved construction, the novel 40 arrangement and combination of parts, and the efficient operation of the machine, which will be hereinafter fully described, and particularly pointed out in the claims.

In the annexed drawings, Figure 1 is a side elevation of a machine embodying my 45 invention. Fig. 2 is a fragmentary and plan view thereof. Fig. 3 is a fragmentary and sectional view showing the actuating mechanism for the tray holder and turner. Fig. 4 is a fragmentary view of the ratchet turning members. Fig. 5 is a sectional detail view of the tray turning member. Fig. 6 is a perspective detail view of the tray-gripping member. Fig. 7 is a perspective detail view of a supporting roller and its 50 bell-crank supporting member. Fig. 8 is an enlarged fragmentary and sectional view of

the machine. Fig. 9 is an enlarged fragmentary and plan view of the machine.

Referring to the drawings, this invention consists of a machine embodying the main side frame members 11 and frame members 12, 13, 14, and 15, and lower frame members 16, connected at the rear to frame members 15, and at the front to transverse frame member 17, supported by the depending 60 frame members 18. The master-wheels 19, are mounted to rotate on independent and fixed hub and axle members 20 projecting inwardly from the side frame members 11. A countershaft 21 is journaled in frame 65 members 16, and is provided at each end with a sprocket pinion 22, driven by the sprocket wheels 23 fixed to the master-wheels and connected by sprocket chains 24 therewith. The sprocket pinions 22, are mounted 70 with ratchet connecting members 25, so that either master-wheel may drive the counter-shaft.

A bearing member 26 projects rearwardly from the frame member 17 and is fixed to 80 frame members 16. The rollers 27 are mounted on shaft 28, journaled in bearing member 26. A countershaft 29 and gear members 30 and 31, form a driving connection between the countershaft 21 and roller 85 shaft 28. The arrangement is such that the roller shaft is driven in a rotary direction contrary to that of the master-wheels.

An auxiliary frame 87 is pivotally connected to brackets 88 projecting from transverse frame member 17. The forward end 90 32 is supported by truck wheels 33, mounted on bearing extensions 34, working in slots 35, in the depending frame members 36. Springs 37 are interposed between the ends 95 of the slots and the bearing extensions 34, allowing the auxiliary frame to tilt laterally in accordance with inequalities of the ground.

A bar 38 is swivelly connected to frame 100 member 12, and may be secured in position on either side of the machine by passing the bolt 39 through bar 38, and the side member extremities 40. A whiffletree 41 is pivotally connected to the bar 38. The driver's seat 105 42 is hooked over the pins 43 on extensions 44 on either side of the machine, and is adapted to be detached by lifting upon the seat. The machine may therefore be driven and operated upon either side of a row of 110 trays. The forwardly extending teeth 45, having rounded extremities 46, are adapted

to contact closely with the surface of the ground, and to convey the trays to the conveyer 47, traveling over the rollers 27 and 48.

The crosshead guides 49 are fixed to the frame members 16 and have slidingly mounted therein the crossheads 50, provided with fixed crank pin members 51 and axle members 52. The crank-pins 51 are connected by links 53, with levers 54 integral with the shaft 55. The fixed axle members have mounted thereon the gears 56, provided with teeth 57, upon half of the periphery 58, in engagement with the racks 59, integral with the crosshead guides. The tray turning members 60 are provided with ratchet pinions 61, and gears 56 are provided with pawls 62 adapted to rotate the turning members 60 and their integral ratchet pinions 61. A non-rotating ratchet pinion 63 is mounted on a non-rotating axle 52, projecting from each crosshead. The turning member 60 is provided with a pawl 64 on each side in engagement with the corresponding non-rotating ratchet pinion 63. Therefore, upon the forward reciprocating motion of the turning member and the crossheads 50, the gears 56 will rotate in a clockwise direction, but the pawls 64 in engagement with the non-rotating ratchet pinions 63, serve to prevent rotation of the turning member. Upon reverse motion of the crossheads, the gears 56 will rotate in a counter-clockwise direction and serve to turn the tray-turning member to reverse position. An operating lever 65 is mounted on either side of the machine. A sliding clutch member 66, is provided with an integral lever arm 67, on either end of the shaft 55, which is journaled in the frame, and a connecting bar 68, connects operating lever 65 with a corresponding lever arm 67. Each sliding clutch member 66 may be thrown into engagement with a corresponding fixed clutch member 69 on shaft 55, which may therefore be operated from either side of the machine. The extreme forward position of the operating levers is shown in full lines in the various figures of the drawings, and in Fig. 8 the rear position of the operating levers is shown in dotted lines. Corresponding positions of the tray-turning member are shown in Fig. 8.

The tray-turning member 60 consists of hollow side members 70 and integral transverse connecting bars 71. Within the side members 70, are mounted the longitudinally reciprocating bars 72 and 73. These are operatively connected by parallel links 74, pivotally connected to lugs 75 projecting from the side members 70. Bars 72 and 73 therefore move simultaneously in opposite directions. The upper movable bars 72 are provided with projecting lugs 76, adapted to engage with cams 77 in the extreme forward position of the turning members, and with cams 78 in the extreme rearward position of

the turning members. The movable bars 72, are provided with swivelly connected tray-gripping members 79, which are provided with inclined cam faces 80, so that the gripping members are pushed aside upon a tray 70 entering the turning member 60. The movable bars 73 are provided with fixed tray-gripping members 81. As the lugs 76 engage with cams 77 or 78, the tray gripping members move apart in opposite directions 75 thereby releasing a tray that may be held by them. A spring 82, connected at one end to bars 73, and at the opposite end to swivel gripping members 79, serves to retract the gripping members to normal position. Rollers 83, mounted on the bell-crank members 84, serve to support the tray within the turning member 60, in all positions except the extreme rear or release position. As each movable bar 72 is actuated by cam 78, 85 as the member 60 approaches its release position, the bell-crank members are actuated by the bar 72 and the rollers are withdrawn from operative position.

In use, the machine may be driven upon either side of a row of trays containing the grapes. The operator will hold the lever 65 in any intermediate position between the extreme forward and the extreme rear positions. As the loaded trays are carried in position by the conveyer 47, they will be carried partly by the conveyer 47 and partly by the rollers 83. The loaded tray may stop in any of the intermediate positions of the turning member. The operator, upon noting that the tray has passed to the rear of cams 78, will pull the operating lever to the extreme rear position, thereby shifting the tray-turning member 60 to the extreme forward position. As the extreme forward and 105 operative position is approached, the cams 78 will engage with and actuate lugs 76, thereby moving the upper gripping members apart and releasing the upper tray, which will fall upon the loaded tray but in reverse 110 position. The upper tray with its bottom upward, is held by the gripping members sufficiently above the loaded tray to clear the contents thereof, but upon release, will drop into close engagement with the loaded tray. 115 The transverse bar 71, of the tray-turning member 60, limits the rearward movement of the loaded tray. When the loaded tray comes into contact with the swivel gripping members 79, the lugs 85 projecting from the 120 inner walls of the turning member, engage with cams 86, on the turning gripping members, which serves to move the opposed tray gripping members slightly apart until the loaded tray has passed the swivel gripping 125 members. Upon release of the swivel gripping members, they are retracted by the springs 82 to engage with the loaded tray. The operator immediately will pull the operating lever to forward position, thereby 130

shifting the tray turning member 60, to extreme rearward position, and during such movement the member 60 is rotated a half of a revolution, thereby reversing the position 5 of the trays, and causing the contents to pass from one to the other of the trays. The bottom tray with the turned grapes, is then released upon completing the rearward and rotary movement of the turning member. The 10 operator then shifts the operating lever to any intermediate forward position of the turning member, and when the next consecutive tray approaches any position to the rear of the cams 78, will repeat the operation, by 15 shifting lever 65 to operative positions. The operation of gathering the trays from the ground is automatic and the turning of the trays is accomplished by manual manipulation of the lever 65.

20 While I have shown the preferred form of my invention as now known to me, it is evident that various changes in the combination, construction, and arrangement of parts, may be made without departing from the 25 spirit of my invention.

What is claimed is:

1. In a tray-turning machine, the combination with a frame, of master-wheels supporting the frame, an auxiliary frame pivotally connected to the main frame, truck-wheels supporting the auxiliary frame, a bearing member projecting from the frame, a belt roller carried by the bearing member, a roller carried by the auxiliary frame, a 35 conveyer arranged to travel over said rollers, a countershaft, sprocket and chain connection between the master-wheels and the countershaft, a shaft and gear connection between the countershaft and the rear conveyer roller whereby the roller is driven in a direction contrary to the rotative movement of the master-wheels, a tray turning member sliding to forward position over the conveyer and to rearward position to clear 40 the conveyer, means for manually shifting the turning member to either position, and means to operate the turning member with a rotary movement during the rearward movement thereof.

50 2. In a device as described, means for gathering the trays consecutively from the ground, means for placing an empty tray over each full tray, means for reversing the position of the trays to shift the contents of the full tray to the empty tray, and means for releasing the tray with the transferred 55 contents.

60 3. In a device as described, the combination with a conveying belt arranged to move the trays from the ground to release position, of a tray turning member adapted to receive the trays from the conveyer belt, means to manually shift the turning member to and fro relative to the conveyer belt, and 65 means for operating the turning member

with a half of a revolution during the rearward movement thereof, means for gripping the tray at any intermediate position of the turning member, and means for releasing the gripping means when the tray-turning member approaches the rearward and release position. 70

4. In a device as described, a tray-turning member, comprising hollow side members, transverse bars connecting the side members at diagonally opposite corners, supports projecting inwardly from the side members, rollers carried by said supports, means for moving the rollers to inoperative position as the turning member approaches the release position for the trays, longitudinal bars mounted within the side members, parallel links connecting the bars whereby they will move simultaneously in opposite directions, a pair of gripping members 75 swivelly mounted on the end of the outer reciprocating bars, inclined faces on the swivel gripping members whereby they are forced out of the way by the loaded tray, cams on the swivel members, lugs projecting 80 from the walls of the side members and engaging with the cams on the swivel gripping members whereby the longitudinal bars are actuated upon angular swivel movement of the swivel gripping members, fixed and oppositely disposed gripping members on the inner reciprocating bars, reciprocating crossheads journaled in the side members, means for manually operating the crossheads with 85 a reciprocating movement, crosshead guides from the walls of the side members and engaging with the cams on the swivel gripping members whereby the longitudinal bars are actuated upon angular swivel movement of the swivel gripping members, fixed and oppositely disposed gripping members on the inner reciprocating bars, reciprocating crossheads journaled in the side members, means for manually operating the crossheads with 90 a reciprocating movement, crosshead guides for the crossheads, toothed rack members integral with the crosshead guides, a pinion rotatively mounted on the crosshead, and operated by engagement with the rack and in opposite rotary directions during the reciprocating movement of the crossheads, ratchet pinions integral with the side members, pawls mounted on the rotary pinions and engaging with the ratchet pinions when the rotary pinions are operated with a counter-clockwise movement, fixed and non-rotating ratchet members integral with the crossheads, pawls mounted on the side members and engaging with the non-rotating ratchet pinions to prevent rotation of the 95 turning members when the rotary pinions are actuated with a clockwise movement. 100

5. In a device as described, a tray-turning member, comprising hollow side members, transverse bars connecting the side members, means for manually shifting the tray-turning member alternately to tray-engaging 105 position, and to tray-releasing position, means for rotating the tray-turning member with a semicircular rotary movement 110 while passing from the tray-engaging position to the tray-releasing position, rollers supporting the tray within the tray-turning member, tray-grippers carried by each side member, means for releasing the tray-grip- 115 120 125 130

- pers which are uppermost in the tray-engaging position, means for releasing the tray-grippers which are lowermost in the tray-releasing position, and means for withdrawing the supporting rollers from operative position simultaneously with the actuation of the tray-grippers in the release position.
6. In a device as described, a tray-turning member, tray-gripping members carried thereby, levers for manually shifting the tray-turning member from tray-engaging position to release position, means for imparting a semicircular rotary movement to the tray-turning member while passing from tray-engaging position to tray-releasing position, means for maintaining the tray-turning member against rotation while passing from tray releasing position to tray-engaging position, conveyer means for passing the trays from the ground to the tray-turning member, tray-gripping members carried by the tray-turning member, means for actuating the gripping members which are uppermost in the tray-engaging position, and means for actuating the tray-gripping members which are lowermost in the tray-releasing position, said tray-turning member passing over the conveyer in the tray-engaging position, and passing to clear the conveyer in the tray-releasing position.
7. In a device as described, a main frame, an auxiliary frame, master-wheels supporting the main frame at the rear, truck-wheels supporting the auxiliary and main frames

at the front, pivotally connected tractor-connecting elements, adapted to be shifted to either side of the machine, means for securing the tractor-connecting elements in operative position on either side of the machine, an operator's seat, means for attaching the seat to either side of the machine, a conveyer extending over the auxiliary frame and adapted to convey the trays to the rear of the machine, sprocket and chain connection whereby the conveyer is driven with the movement of the master-wheels, a tray-turning member, crosshead guides on the frame adjacent to the conveyer, crossheads sliding therein, and supporting the tray-turning member, ratchet mechanism to operate the tray-turning member with a semicircular movement when passing from tray-engaging position over the conveyer to the releasing position, ratchet mechanism serving to prevent rotation of the tray-turning member when passing from tray-releasing position to engaging position, tray-gripping members carried by the tray-turning member, a transverse shaft at the rear of the frame, lever arms depending therefrom, bars connecting the lever arms and said crossheads, a lever on either side of the machine for operating said transverse shaft, and a clutch mechanism for throwing either manually manipulated lever into operative connection with the transverse shaft.

In testimony whereof, I hereunto affix my signature.

KATSUJIRO SANWO.
